Assistant Examiner — Yelizaveta Y Masalimova

(74) Attorney, Agent, or Firm — Rothwell, Figg, Ernst & Manbeck, P.C.

(57) CLAIM

The ornamental design for a shoe, as shown and described.

DESCRIPTION

FIG. 1 is a perspective view of the front, top, and right side of the shoe;

FIG. 2 is a front view of the shoe;

FIG. 3 is a rear view of the shoe;

FIG. 4 is a left side view of the shoe;

FIG. 5 is a right side view of the shoe;

FIG. 6 is a top view of the shoe; and,

FIG. 7 is a bottom view of the shoe.

The even-dashed broken lines shown in the drawings depict stitching and form no part of the claimed design. The dot-dot-dash broken lines shown in the drawings depict portions of the shoe that form no part of the claimed design.

1 Claim, 7 Drawing Sheets
